Patented Nov. 22, 1927.

UNITED STATES PATENT OFFICE.

ALVIN G. SHERMAN, OF GROSSE POINTE PARK, MICHIGAN, ASSIGNOR TO THE DETROIT VAPOR STOVE COMPANY, OF DETROIT, MICHIGAN, A CORPORATION OF MICHIGAN.

STOVE CONSTRUCTION.

Application filed January 13, 1927. Serial No. 160,790.

This invention relates to stove construction and particularly to a manifold for supplying the fuel to the various burner structures, and method of forming same.

5 In gas and vapor stoves and other similar structures the present tendency is toward enameled stoves and designs which make for cleanliness and sanitarness, and which in general, results in a very pleasing article 10 of manufacture. Such enameled surfaces in addition to being sanitary may be very easily cleaned by merely wiping with a wet cloth. Many attempts have been made to enamel the manifold structure so as to match 15 up and synchronize with the other enameled parts of the stove, as a stove with a porcelain enameled manifold presents a much more pleasing effect with a stove which is porcelain enameled with a nickled 20 manifold. However, these attempts to secure a porcelain enameled manifold have been unsatisfactory, mainly for the reason that the porcelain enameling of a wrought iron, steel or cast iron manifold is mechanically impractical and the resulting product, 25 if attempted, is generally full of blisters and is generally unsightly in appearance.

It is the object of the present invention to provide a porcelain enameled manifold 30 structure which completely harmonizes with the porcelain enameled parts of the stove structure, and the enameled surface of which is smooth and even to correspond with the porcelain enameled surfaces of the stove.

35 In the drawings:

Fig. 1 is a fragmentary perspective view of a stove embodying my novel manifold structure, also illustrating the prominence of the manifold at the front of the stove.

40 Fig. 2 is a detail view of the manifold structure itself showing the enameled manifold shell broken away.

Fig. 3 is a sectional view taken on line 3-3 of Fig. 2 and illustrating the positioning of the auxiliary conduits, or valves, whereby to hold the enameled shell in place 45 relatively to the rough conduit.

Fig. 4 is a fragmentary longitudinal sectional view of one end of the manifold structure illustrating particularly the recessed cap fitting and the manner of positioning the enameled manifold within the recessed portion of the cap.

50 Figs. 5 to 8 are progressively arranged 55 views, partly diagrammatic, illustrating the

manner of forming my novel enameled manifold 2, and the manner of assembling the same, Fig. 5 showing the plain sheet metal stock, Fig. 6 illustrating the manner of punching the same, Fig. 7 showing the manner of rolling the same to form the tube, and Fig. 8 the manner of assembling the enameled tube over the rough cast or wrought iron or steel pipe.

In Fig. 1 of the drawings I have shown my novel porcelain enameled manifold as it appears with respect to the stove structure, and it will be noted that this manifold is one of the most prominent parts of the stove and it will be obvious that when the same is porcelain enameled with the same smooth, even finish as the other porcelain enameled parts of the stove that it will present what may be termed a very beautiful stove structure, and will materially assist in taking the stove 70 out of the class of an ordinary cooking implement and make it an article of beauty. In providing a porcelain enameled manifold structure I do not attempt to in any way porcelain enamel the surface of the 75 manifold pipe itself, whether of wrought iron, cast iron or steel, but this pipe is left in its rough unfinished state as received from the manufacturer.

Instead of utilizing the rough manifold 80 pipe itself I preferably take a strip of sheet steel, which may be of 22 gage Armco iron, or any suitable sheet metal stock may be used as desired. This stock is flat, as shown in Fig. 5 and may be designated 1, and is preferably of a width so that after being rolled up it will be of a diameter so as to easily slip over the rough manifold pipe. Before rolling up the piece of stock 1, I preferably fabricate the same by punching out suitable 85 holes 2, which are spaced to correspond to the spacing of the valves 3 which lead from the rough manifold pipe. The piece of stock 1 may then be rolled up by any suitable means so as to present a tube, as shown in 90 Fig. 7, which has an inside diameter slightly greater than the outside diameter of the rough manifold pipe and which is provided with suitable apertures 2 to register with the valve structures. The seams of this tube 95 may be joined in any manner desired.

After the tube has been fabricated it may be porcelain enameled in the same manner as the various other sheet metal plates going to make up the general stove structure. The 100 110

shell or tube being of sheet metal it will be just as easily porcelainized as the other pieces of sheet metal stock and will take a smooth, even porcelain finish which will match perfectly with the porcelain finish on the other parts of the stove.

This porcelain enameled tube may then be slipped over the rough manifold conduit until the apertures 2 match with the tapped holes in the rough pipe. The valve members 3 may then be screwed into place in the normal manner and the apertures 2 will cooperate with these valve members 3 to hold the porcelain enameled tube securely in place.

In order to present a still more pleasing appearance I have provided special pipe fittings for the ends of the porcelain enameled manifold tube. These special fittings consist of an elbow 4 and a cap 5. The cap and elbow are preferably recessed, as at 6, so as to nicely fit over the ends of the porcelain enameled tube, as clearly shown in Fig. 4. The elbow and cap are preferably standard nickelized fittings.

It will therefore be seen that I have provided a new article of manufacture, namely, a porcelain enameled manifold, the enamel finish of which is smooth and uniform corresponding exactly with the enamel finish of the other parts of the stove. It will further be obvious that this porcelain enameled manifold is a very simple and cheap construction and completely does away with the necessity of nickelizing the rough manifold conduit. The structure is very easily assembled and presents an easily cleanable surface, the only nickel parts being the special

cap and elbow fittings which are readily accessible for cleaning and which are also positioned out of the way so as not to be subject to the necessity of as frequent cleaning as the manifold structure.

What I claim is:

1. A manifold structure for stoves, or similar articles, comprising a relatively rough conduit for supplying fuel to burners, auxiliary conduits leading away from said main conduit, an enameled shell fitting around said main conduit and provided with suitable apertures registering with said auxiliary conduits.

2. A manifold structure for stoves of the type having enameled surfaces, comprising a main conduit for supplying fuel to the burners, auxiliary conduits leading away from said main conduit, special fittings at each end of said main conduit, and an enameled shell, corresponding in appearance to the enameled surfaces of the stove, fitting around said main conduit and provided with suitable apertures registering with said auxiliary conduits, the ends of said enameled shell being positioned within said special fittings.

3. A manifold structure for stoves of the type having enameled surfaces, comprising a relatively rough main conduit for supplying fuel to the burners, auxiliary conduits leading away from said main conduit, and an enameled sheet metal shell, corresponding in appearance to the enameled surfaces of the stove and fitting around said main conduit.

In testimony whereof I affix my signature.

ALVIN G. SHERMAN.
